UNITED STATES PATENT OFFICE

EDWARD C. ADDISON, OF CAMDEN, NEW JERSEY, AND WARREN H. HILL, OF PHILADELPHIA, PENNSYLVANIA, ASSIGNORS TO R. H. BEAUMONT COMPANY, OF PHILADELPHIA, PENNSYLVANIA, A CORPORATION OF PENNSYLVANIA

REVERSIBLE DOUBLE DIGGING EDGE SCRAPER

Application filed April 3, 1930. Serial No. 441,229.

The subject of our invention is a scraper for use with coal storage or like systems, which has two digging edges.

Another feature of our improved scraper 5 is that the towing means is attached in the vertical center of the forward edge of the scraper.

A further feature of our improved scraper is that there is that there is provided a bail 10 or brace in the vertical center of the front edge of the scraper.

Yet another feature of our improved scraper is that there are provided flexible adjustable connections between the horizontal 15 center of said bail and the towing means for said scraper and between said bail and the rear of said scraper.

For a further exposition of our invention reference may be had to the annexed drawings and specification at the end whereof our 20 invention will be specifically pointed out and claimed.

In the drawings,

Figure 1 represents a plan view of our improved 25 scraper.

Figure 2 represents a side elevation of our improved scraper.

Figure 3 is a detailed cross section on line A A of Figure 1.

Our improved scraper consists of two arms 30 1 and 2 joined together at a divergent angle at the rear of the scraper. Each of said arms has an upper and a lower cutting edge 3 and 4 respectively. These cutting edges may be 35 made removable if so desired and may have attached thereto detachable digging teeth 5. At their forward ends, arms 1 and 2 terminate in straight side plates 6 and 7. At their forward ends said straight side plates 6 and 40 7 terminate in continuous digging edges 8 and 9 which may be made detachable and which may be made of harder material than the remainder of the scraper. A suitable example of such a material is manganese steel 45 which gives added stiffness and greater wearing qualities to said digging edges.

In the vertical center of said side plates 6 and 7 there is mounted a bail generally indicated at 10. As is more clearly seen in Figure 50 3, said bail consists of a reenforcing plate 11

having fastened to its upper and lower faces channel bars 12. Attached to the edges of the channels and passing over the edges of the reenforcing plate and welded or otherwise fastened to said channels are plate deflectors 13 of curved shape forming an arrow head shape in vertical cross section.

Attached at the vertical center of the forward edge of the side plates 6 and 7 are shackles 14 and 15 pivotally mounted or otherwise fastened thereto. These shackles serve for the attachment of the front bridle chains 16 or for the attachment of other towing means. Bridle chains 16 lead to a ring 17 to which cable 18 or other towing means is attached. Between ring 17 and the horizontal center of bail 10 there is provided a flexible adjustable connection. Our preferred embodiment of such a connection is a chain 19 having a turn-buckle 20 therein which serves to keep the chain taut. Between the horizontal center of the bail and the rear of the scraper there is also provided a flexible connection. Such a connection may be suitably provided by a chain 21 leading to a swivel eye 22 which is adjustably attached to the scraper arms 1 and 2 by nuts 23 or other suitable attachment.

Connection for a cable or other towing means is provided at the rear of the scraper 80 by pivotally mounted clevises which carry rear bridle chains 25 which terminate in a ring 26.

In order that our scraper may be capable of digging on either horizontal edge it is important that the connection for the towing means be made at the vertical center of the forward edge of the scraper. Such connections are provided by shackles 14 and 15 and by bail 11.

It is likewise important to provide a flexible connection between the horizontal center of bail 11 and the towing means. This is necessary because of the fact that when the scraper is being used a pull is exerted on the bridle chains 16 in front which has a tendency to pull arms 1 and 2 of the scraper together. Chain 19 is provided to take part of this pull and may be kept suitably taut for that purpose. Chain 21 is also provided to transmit

this strain directly to the back of the scraper.

It is also advantageous and important to provide the straight digging edges 8 and 9 as these provide a large straight cutting edge which digs into the material being moved. These edges keep the scraper traveling in a straight path and prevent "snaking" or deviation of the scraper from its proper path. Drag scrapers are frequently operated so as to dig a deep trench in the material being worked on and the edges 8 and 9 guide along the walls of such a trench and present a large sharp cutting edge.

We do not intend to be limited in the practice of our invention save as the scope of the prior art and of the attached claims may require.

We claim:

1. A scraper having divergent arms, a bail connecting said divergent arms at the vertical center of their forward ends, means for towing said scraper means for attaching the towing means for said scraper to the horizontal center of said bail, and a flexible connection between the horizontal center of said bail and the rear of said scraper.
2. A scraper having divergent arms, a bail connecting said divergent arms at the vertical center of their forward ends, attaching means provided at the vertical center of the forward ends of said arms, means for towing said scraper, flexible connections between said towing means and said attaching means, a flexible connection between said towing means and the horizontal center of said bail, and a flexible connection between the horizontal center of said bail and the rear of said scraper.
3. A scraper having divergent arms, a bail connecting the forward ends of said arms at their vertical center, curved plates forming the front and rear surfaces of said bail, attaching means at the vertical center of the forward ends of said arms, means for towing said scraper attached to said attaching means, and a flexible connection between said towing means and the horizontal center of said bail.
4. A scraper having divergent arms, a bail connecting the forward ends of said arms at their vertical center, curved plates forming the front and rear surfaces of said bail, attaching means at the vertical center of the forward ends of said arms, means for towing said scraper attached to said attaching means, a flexible connection between said towing means and the horizontal center of said bail, and a flexible connection between the horizontal center of said bail and the rear of said scraper.

EDWARD C. ADDISON.
